PAUL P. HORNI, OF NEWARK, NEW JERSEY

INTERLOCKING KEY ASSEMBLY

Application filed January 27, 1928. Serial No. 250,020.

This invention relates to an assembly of keys that is provided with interlocking means to insure against operating the keys in any way that would cause contradictory results.

When a series of keys is associated together on a keyboard for example, it becomes desirable to provide means whereby only one key at a time can be made to function. When two 10 or more keys are simultaneously operated, they might produce contradictory results or interfere in some way or other with their producing their destined function.

One use to which such apparatus may be applied is to control circuits used for operating signals such as for example traffic signals or signals for conveying information by signs or lights from or to a moving vehicle. In such case, it is desirable that the operation of 20 any key to set a given signal shall not function in any way to give a signal that will be contradictory to signals already set. A particular object of this invention is to provide means whereby the operation of any key to 25 set any signal will automatically release any signal inconsistent with it.

A further object of the invention is to prevent the functioning of two or more keys when by error or design an attempt is made 30 to operate them simultaneously. The invention comprises a combination of a plurality of keys and interlocking mechanism that will accomplish the above objects.

In the accompanying drawings a specific 35 embodiment of my invention is shown as applied to electric switches for operating traffic signals.

In the drawings:

Figure 1 is a longitudinal section through 40 the keyboard.

Figure 2 is a plan view of the interlocking bars.

Figure 3 is a perspective view of an individualized key and its corresponding interlocking plates.

Referring to the drawings, 1 to 6 represent manually operable members which in this case are switches which may be assembled in a suitable casing 7. Each switch has 50 a spring 8 for holding it in one position which

in the instance shown is in the open position, although it might also be in the closed position. The contacts are shown at 9. At 10 is shown an interlocking bar which is held in a retracted position by a spring 11. This bar is supported on guides 12 and has a certain amount of end play thereon. Switches 2 to 6 inclusive are provided with notches 13 which, when any switch is depressed, engages with the interlocking bar 10 and holds that switch in the contact-making position. Each of the switches 1 to 6 is also provided with a cam 14 which operates upon the depression of any switch to push the interlocking bar 10 against the effect of the spring 11 to a position that will release any switch held down by the interlocking bar. The switch 1 is solely for this purpose and does not operate to make any contacts but simply is a release switch for throwing out of action 60 any switch that may be closed without at the same time closing any contacts. In order to prevent absolutely the simultaneous operation of any two or more of the switches, I provide interlocking plates 15 of which four 65 are shown, two upper ones and two lower ones. Each of the switches has key bars 16 of various lateral widths, one width for each of the plates 15, which operate in such a way that when a switch is depressed the plates will be so arranged that side bars or wings 17 on the particular switch being depressed will pass through slots 18 on the plates. When 70 any switch is thus depressed, the plates will be so shifted transversely that the side wings 17 on any other key will not register with the slots 18 in its particular location and therefore such other switch cannot be depressed. The plates 16 are beveled on the 75 lower ends as shown so as to act as cams in shifting the plates. Springs 19 serve to hold the interlocking plates 15 in a retracted position and supports 20 hold the plates with a certain amount of longitudinal play. It 80 is evident that the switches may be either held in the contact-making position by the notches 13 or in case of closed circuit systems they might be held in the open circuit 85 positions.

It is evident also that instead of springs 8, 11 and 19, gravity or any other force may be used to retract the switches.

While I have shown the application of the invention to the particular case of a multiple switch for controlling traffic signals, the principle of the invention may be equally well applied to any system of manually operable members assembled together to produce a variety of results.

I claim:—

1. An interlocking key assembly comprising a plurality of manually operable members, each tending to assume the open position, an interlocking bar engaging a plurality of the members, means on each of said members for shifting the interlocking bar to a different position when a member is closed from the position that it would be placed by the operation of any other of said members, and means on each member for permitting the closure of only one of said members at a time by said interlocking bar.
2. A construction according to claim 1 in which a plurality of interlocking bars are combined with a plurality of bar operating keybars on the members to produce separate combinations of relative position of the bars for each member when operated.
3. A construction according to claim 1 in which a plurality of interlocking bars are combined with a plurality of bar operating keybars on the members to produce separate combinations of relative position of the bars for each member when operated, with means on each member preventing its arrival at its functioning position when the bars are set by any other member.
4. An interlocking key assembly comprising a plurality of manually operable key members, each tending to assume the open position, an interlocking bar engaging all the members, the key members being provided with beveled key bars of various widths and the interlocking bar being movable transversely by the key members and having slotted openings through which the said key bars are adapted to pass, each key member when depressed setting the interlocking bar to a position permitting only such operating key to pass to its depressed position.
